CLARENCE C. FLEMING, OF AMITYVILLE, NEW YORK, ASSIGNOR TO EBERHARD FABER PENCIL COMPANY, OF BROOKLYN, NEW YORK, A CORPORATION OF NEW YORK.

DISPLAY-RACK.

1,125,681.

Specification of Letters Patent.

Patented Jan. 19, 1915.

Application filed December 4, 1913. Serial No. 804,587.

To all whom it may concern:

Be it known that I, CLARENCE C. FLEMING, a citizen of the United States, residing at Amityville, in the county of Suffolk and State of New York, have invented certain new and useful Improvements in Display-Racks, of which the following is a specification.

This invention relates to display-racks of the character employed to a considerable extent in exhibiting pencils, penholders and the like for sale.

The invention is directed to the provision of a display-rack of an improved construction which makes it possible to give to the rack a distinctive and attractive appearance.

In accordance with the present invention, a display-rack is provided in the form of a receptacle for holding pencils and penholders and combined with this is a wall parallel to and spaced apart from one of the side-walls of the receptacle, this wall being cut away along one or more of its edges so that it is of less size than the adjacent parallel wall of the receptacle. By reason of this arrangement of the side-wall and the additional wall, the latter being spaced from and of less area than the former, it is possible to apply decoration to the device which is both distinctive and attractive, a panoramic effect being obtained when the decoration is applied partly to the additional wall and partly to the adjacent side-wall. In accordance with the invention, this added wall of the structure is so mounted upon the receptacle that it may be moved to its operative position or to an inoperative position in which it lies flat against the side of the receptacle so that the rack requires no more space for storage or shipment than it would if it were not provided with the additional wall. Also, means are provided for holding the wall in its operative position spaced apart from and parallel to a side-wall of the receptacle. This means preferably consists of a flap integral with the wall and adapted to be moved into coaction with the side-wall of the receptacle or to a position in which it lies against the bottom of the receptacle in which latter position it permits movement of the wall against the side of the receptacle.

The preferred embodiment of the inven-

tion is illustrated in the accompanying drawings, in which—

Figure 1 is a perspective view of the display-rack and Figs. 2 and 3 are vertical sections of the rack showing the wall in its operative and inoperative positions.

Referring to these drawings, a display-rack is shown for holding pencils and penholders in vertical position. The rack itself may be of the usual or any suitable construction. In the drawings, it is shown as consisting of a rectangular box 4 having two partitions 5 secured therein in horizontal position. These two partitions are provided with a multiplicity of holes in vertical alignment into which pencils may be inserted. This receptacle has a wall 6 applied thereto, this wall being arranged parallel to and normally spaced apart from one of the side-walls of the receptacle. Also, it is cut away along one edge as shown in Fig. 1 so that it is of substantially less area than the adjacent side-wall of the receptacle. The wall 6 has integral extensions 7 at its ends which are secured to the receptacle 4 preferably by pasting them to the ends of the receptacle. The extensions 7 project laterally from the ends of the receptacle 4 and these projecting parts 8 are creased as is indicated in the drawings. By reason of the provision of these foldable portions in the extensions 7 integral with the wall 6, the wall may be moved toward and away from the adjacent side-wall 9 of the receptacle. When the wall 6 is so moved, it is carried against side-wall 9 of the receptacle; the portions 8 of the extensions 7 folding to permit such movement of the wall 6. The wall is shown in its outer or operative position in Figs. 1 and 2, but in Fig. 3 it has been moved up against the side-wall 9 of the receptacle.

Means are provided for holding the wall 6 in its outer or operative position and maintaining it substantially parallel to the side-wall 9 when in that position. This means preferably consists of a flap 10 integral with the wall 6 at the bottom edge of that wall. This flap 10 has a crease therein so that its outermost portion may be moved to a vertical or horizontal position. When the wall 6 is against the wall 9 as shown in Fig. 3, the flap 10 lies against the bottom of the receptacle. But when wall 6 is moved

to its outer position, the flap 10 may be folded and its outermost portion turned up against the side-wall 9 of the receptacle in which position it serves to sustain the wall 6 parallel to and at a definite distance from the wall 9. With a display-rack constructed in this manner, it is possible to secure distinctive and attractive appearances by the application of decoration to the walls 6 and 10, utilizing in such decoration the panoramic effect obtainable by reason of the spacing apart of these walls and the exposure of a portion of the rear wall over the edge of the front one. The construction whereby 15 these more attractive and distinctive effects are obtained is such, however, that the additional parts combined with the rack occupy practically no more space than when the rack is not used.

Having described my invention, what I claim as new therein and desire to secure by Letters Patent of the United States is:

1. A display-device comprising the combination of a body portion having a wall, 25 a wall substantially parallel to but adapted to be spaced apart from said body wall, means for securing said movable wall to said body portion, permitting movement thereof to extended position, or position 30 against said body wall, and means for holding said movable wall in extended position, adapted to permit folding of said wall against said body wall when desired, said movable wall being of less area than said 35 body wall, and said movable wall and the portions of said body wall which are not hidden by said movable wall carrying jointly a pictorial representation and being so positioned when said movable wall is 40 extended, and the parts of said representation being so arranged that the said parts representing objects in the foreground are carried by said movable wall, and a panoramic effect is produced by the representation 45 carried by the walls jointly, substantially as set forth.

2. A display-device comprising the com-

bination of a support, a wall substantially parallel to but adapted to be spaced apart from said support, means integral with said 50 wall for mounting the latter upon the support permitting movement of the wall toward and away from the support, and means integral with said wall for holding the wall at a predetermined distance from 55 said side-wall and adapted to permit movement of said wall against said receptacle when desired, said wall being cut away so that it is of less area than said side-wall of the receptacle, and said movable wall and 60 the portions of said side-wall which are not hidden by said movable wall carrying jointly a pictorial representation, the parts of which representing objects in the foreground are carried by said movable wall, 65 substantially as set forth.

3. A display-device comprising the combination of a support, a wall substantially parallel to but spaced apart from said support, means for mounting said wall upon 70 the support permitting movement of the wall toward and away from the support, and a flap integral with said wall and adapted to extend into engagement with said support to space the wall therefrom 75 or to lie against the bottom of the support when said wall is moved close to the support, substantially as set forth.

4. A display-device comprising the combination of a support, a wall disposed substantially parallel to the support, integral extensions at the ends of said wall secured to the support and having foldable portions therein permitting movement of said wall toward and away from the support and an 85 integral flap on said wall movable into and out of contact with the adjacent wall of the support, substantially as set forth.

This specification signed and witnessed this 1st day of December, 1913.

CLARENCE C. FLEMING.
